SPOT CARBON FORM SHEET PACK

Charles W. Potter, Waltham, Mass., assignor to
 Atlantic Register Company, Waltham, Mass., a
 corporation of Massachusetts

Application September 23, 1942, Serial No. 459,394

1 Claim. (Cl. 282—12)

This invention relates to a pack of form sheets of combined record and transfer character and has for its object an arrangement of improved utility and economy of manufacture of said packs.

A combined record and transfer sheet has upon one face a printed form with blank spaces to be filled in and has applied to the opposite face corresponding to said blank spaces, spot coatings of carbon transfer ink whereby any filled in entries upon the upper face may be transferred in carbon copy form to a second sheet underlying the same. These record-transfer sheets are relatively thin and somewhat translucent. However, they usually have sufficient weight and sizing to prevent ordinary printing from showing through, but they are generally not sufficiently opaque to prevent the darkened spot carbon applications from showing through the translucency of the sheet. One of the objects of the present invention is to eliminate this showing through of the carbon spots without making the sheet unduly expensive and heavy in weight.

The pack is conveniently formed from a strip of several form sheets joined by lines of weakness and a further object of the invention is to provide a folded pack whereby the underlying sheets will be in proper relation to receive the carbon transfer impressions thereon as desired and also so that the completed pack will present but a single folded edge for being introduced into the typewriter. It is more difficult to maintain several superimposed sheets of a pack in proper registration when the pack has a plurality of leading edges which must be introduced into the typewriter.

Referring to the drawing which shows a preferred embodiment of the invention,

Fig. 1 is a top side view of a strip of several form sheets, here shown as four in number;

Fig. 2 is an under side view of the same strip;

Fig. 3 is a view showing one manner of folding the strip in accordance with the invention;

Fig. 4 is a view showing another manner of folding said strip in accordance with the invention; and

Fig. 5 is a sectional view along line 5—5 of Fig. 2 to show superposed coatings on the transfer side of the sheet.

It will be understood that the thickness of the sheets and coatings are greatly exaggerated in the views for the purposes of illustration.

Referring particularly to the drawing, the strip as a whole is indicated at 5 and is made up of several form sheets, four in number, 1, 2, 3, and 4. However, the number of sheets making up

the strip is not important. The lines of weakness joining the adjacent sheets are indicated at 6 and along these lines the sheets may eventually be separated from one another.

As shown in Fig. 1, the lowermost sheet 1 which is intended to be the uppermost sheet of the pack when folded, has printed thereon any desired form with certain blank spaces 7, 8, and 9, adapted to be filled in in accordance with the use of the form. In Fig. 2 the reverse sides of the sheets of Fig. 1 are indicated as 1', 2', 3', and 4', respectively. The under side 1' of sheet 1 for instance is blank except for certain restricted areas thereof indicated at 7', 8', and 9', which areas correspond approximately to the blank areas 7, 8, and 9 of the upper face of said sheet.

The areas 7', 8', and 9' are treated with spot carbon applications of any suitable carbon ink which will transfer in the usual manner, any impression made on the corresponding upper side of said sheet. However, before said spot carbon transfer ink applications are made to the areas aforesaid, these areas first have applied thereto a coating of color material, preferably of the same tint as the body of the sheet to which it is applied and being of sufficient body to render said areas substantially opaque or at least more opaque than the balance of the sheet.

The purpose of these color coats in the aforesaid restricted areas 7', 8', and 9' is to furnish a background or base body for the carbon transfer ink later applied thereto, and particularly so that said darkened spots of carbon ink will not show through the body of the sheet 1 and be apparent from its upper side in the areas 7, 8, and 9. The superposed applications of the color coat and carbon transfer ink are shown in Fig. 5 wherein said color background is indicated at 10 and the carbon transfer ink 11. It will be understood that in this view the sections of the said coating are greatly exaggerated and that on the actual sheet there will be no apparent difference in thickness of the sheet at the places where these superposed coatings are applied. The color application 10 may be of any suitable paper coating of non-transferable material, for instance a white ink may be used on white paper. The method of applying the coat 10 as well as the carbon transfer ink 11 may be by suitable successive printing operations.

The remaining sheets of the strip, viz. 2, 3, and 4, will likewise have printed thereon the forms similar to that on sheet 1 although there might be slight changes in said forms in accordance with the use of the same. Due to the manner of

folding the sheets into the pack as will be hereinafter described the printed form on sheets 2 and 4 will be on the opposite side of the strip to that printed on sheets 1 and 3 as clearly appears from Fig. 2. All of the sheets are treated on the sides opposite the printed side with the applications of background color and carbon transfer ink as previously described in connection with sheet 1, except for the sheet which is eventually to be the lowermost sheet in the pack, namely sheet 2 in Fig. 1. This sheet on its upper side (as seen in Fig. 1) is to be left entirely blank because in the four sheet pack shown there are no sheets beneath it to receive the transfer im-
pressions.

Fig. 3 shows one manner of folding a strip of four sheets into a pack in order to bring the sheet 1 to uppermost position and sheet 2 to the lowermost position. In this form of the pack the entire strip is folded once in its middle and then the folded portions are again folded in the middle, the folds taking place along the weakening lines. In order to have the folded pack lie as flat as possible it is also desirable that the sheets 1, 2, 3, and 4 shall be of very slightly reduced area successively.

Fig. 4 shows another manner of folding the pack from a strip of four sheets. In this form of pack also it will be observed that sheet 1 is uppermost and sheet 2 is lowermost. The ad-
vantage of both these ways of folding a sheet

into its pack is that a single embracing fold, indicated at 12 in Fig. 3 and at 13 in Fig. 4, is presented as the leading edge of the pack for being led into the typewriter when the folded pack is introduced for being typed. This arrangement makes the folded pack substantially equivalent to a single sheet with respect to its convenience in being so introduced into the typewriter. In the usual form of pack when several edges are presented as the leading edges for being introduced into the typewriter they are apt to cause a disarrangement of the sheets and imperfect registration of the carbon spots with the blanks to be filled in. This difficulty is avoided by having the pack with a single folded leading edge.

What I claim is:

A pack of form record sheets in superposed relation, each sheet having upon its upper face a printed form with one or more blank spaces to be filled in, and each of said sheets except the bottom sheet of the pack having a spot application in a restricted space or spaces to correspond to said blank space or spaces of its upper face, first a color coat of the same tint as the body of the sheet and of non-transferable material to render said space or spaces substantially opaque in contrast to the balance of the sheet and then superposed upon said color coat a coating of transfer ink.

CHARLES W. POTTER.
